(57) **CLAIM**

The ornamental design for a controller housing for extracorporeal treatment, as shown and described.

DESCRIPTION

FIG. 1 is a front, top, left side perspective view of the controller housing for extracorporeal treatment;

FIG. 2 is a front elevational view of the controller shown in FIG. 1;

FIG. 3 is a rear elevational view of the controller shown in FIG. 1;

FIG. 4 is a left elevational view of the controller shown in FIG. 1;

FIG. 5 is a right elevational view of the controller shown in FIG. 1;

FIG. 6 is a top plan view of the controller shown in FIG. 1; and,

FIG. 7 is a bottom plan view of the controller shown in FIG. 1.

The broken line showing in FIG. 3 is for illustrative purposes only and forms no part of the claimed design.
